L. G. STURDY

CIRCUIT CONTROL EXTENSION FOR ELECTRIC LAMPS

Filed June 2, 1921

UNITED STATES PATENT OFFICE.

LEONARD G. STURDY, OF JOLIET, ILLINOIS.

CIRCUIT-CONTROL EXTENSION FOR ELECTRIC LAMPS.

Application filed June 2, 1921. Serial No. 474,432.

To all whom it may concern:

Be it known that I, LEONARD G. STURDY, a citizen of the United States, residing at Joliet, in the county of Will and State of Illinois, have invented certain new and useful Improvements in Circuit-Control Extensions for Electric Lamps, of which the following is a specification.

This invention relates to circuit control devices for electric lamps and the like and the primary object of the invention is to provide an improved pendant switch for removable association with the lamp plug and socket for controlling the flow of current there-through to the lamp, thereby eliminating the inconveniences generally contingent with the lighting of over head electric lamps, which are not provided with wall switches.

Another object of the invention is to provide a removable control switch for lamp sockets embodying an insulating body for connection with an ordinary lamp socket and arranged to receive an ordinary electric lamp, the body having formed therein a pair of spaced contacts, which are adapted to be engaged, by a pair of spaced contacts carried by a removable cap member, which has associated therewith an ordinary type of pendant switch, the pendant switch forming a convenient means for controlling the flow of current, without necessitating the reaching to a considerable height for engaging the usual lamp switch.

A further object of the invention is to provide a novel means for arranging the spaced contacts in the insulating body and a novel means for connecting the contacts in the body and for holding the parts of the body in place against accidental displacement.

A still further object of the invention is to provide an improved pendant switch attachment for lamp sockets of the above character, which will be durable and efficient in use, one that will be simple and easy to manufacture, and one which can be placed upon the market at a reasonable cost.

With these and other objects in view, the invention consists in the novel construction, arrangement and formation of parts, as will be hereinafter more specifically described, claimed and illustrated in the accompanying drawings, forming a part of this specification, in which drawings:

Figure 1 is a diagrammatic view illus-

trating the novel arrangement of the contact members.

Fig. 2 is a transverse section taken on the line 2—2 of Figure 3 through the improved device.

Fig. 3 is a vertical longitudinal section through the improved device taken on the line 3—3 of Figure 5.

Fig. 4 is a similar view taken at right angles to Figure 3 on the line 4—4 of Figure 5.

Fig. 5 is a top plan view of the improved device.

Fig. 6 is a detail transverse section taken on the line 6—6 of Figure 4, and

Fig. 7 is a detail section taken on the line 7—7 of Figure 3.

Referring to the drawings in detail, wherein similar reference characters designate corresponding parts throughout the several views the letter A indicates the plug portion of the improved circuit control extension and B the removable cap member for association with the plug portion.

The plug portion A includes an insulating body preferably formed of porcelain and includes an upper section 10 and a lower section 11. The body portion is preferably formed in these two sections, in order to facilitate the assembling of the plug portion and the contacts therein. The upper end of the section 10 is reduced in diameter as at 12 and has arranged thereon the threaded contact sleeve 13, which is adapted to be threaded into an ordinary lamp socket. The threaded sleeve 13 is provided with a pair of inwardly extending diametrically opposed attaching lips 14 which are seated in suitable recesses 15 formed in the upper face of the section 10.

The lower end of the section 11 is provided with an inwardly extending bore 16 in which is fitted a threaded contact sleeve 17, which is adapted to receive the base of an ordinary electric lamp. This contact sleeve 17 at its upper or inner end is also provided with a pair of inwardly extending attaching lips 18, which are seated in suitable recesses 19 formed in the inner wall of the bore 16.

The sections 10 and 11 are provided with a pair of spaced parallel aligned bores 20 which receive suitable retaining and conducting bolts 21. As shown these bolts extend through the attaching lips 14 of the

contact sleeve 13 and through the sections and attaching lips 18 of the contact sleeve 17. The inner ends of the bolts have fitted thereon suitable retaining nuts 22. Thus it 5 can be seen that these bolts 21 perform a triple function, first to attach the contact sleeve 13 in position, second to connect the sections 10 and 11 together, and third to electrically connect the contact sleeves 13 10 and 17 together and to hold the contact sleeve 17 in position.

The section 10 is also provided with a centrally disposed bore 23 which receives the central contact bolt 24, the upper end of 15 which engages and retains in place the central contact plate 25, which is adapted to engage the ordinary central contact of the lamp socket. The inner end of this bolt 24 is electrically connected with a contact strip 20 26 which is formed on the contact member 27 of the pair of contact members 27 and 28. These contact members 27 and 28 have their bases embedded in suitable recesses 29 formed in the inner face of the section 11 25 and are retained in place by suitable contact screws 30. One of the contact screws 30 holds in place the central spring contact member 31 which is located within the bore 16 at the central portion thereof and forms 30 the central contact which is adapted to be engaged by the central contact of an ordinary lamp base. Each of the contact members 27 and 28 include upstanding resilient contact legs 32 which extend outwardly from 35 the inner face of the section 11. The inner or lower face of the section 10 is provided with a pair of spaced inwardly extending notches 33 which are adapted to receive the spring contact legs 32 and these notches 33 40 open out through one side face of the plug A, which face is flattened as at 34 in order to snugly receive the cap B.

By this arrangement of the spaced contacts 27 and 28 the circuit through the central contacts 25 and 31 is normally broken 45 and it can only be closed by the bridging of the contact members 27 and 28.

The cap member B can be of the usual or any preferred construction and includes 50 the hollow insulating body 35 which has secured therein the outwardly extending spaced contact tongues 36 which are adapted to be inserted in the notches 33 into engagement with the resilient legs 32 of the contact members 27 and 28. These contact tongues 36 have electrically connected thereto conductor wires 38 which may have electrically connected thereto any suitable or

preferred type of electric switch or circuit 60 closer 39. By this construction it can be seen that when the body 35 is placed in position and the switch 39 operated so as to close the circuit, the contact 27 and 28 will be bridged allowing the circuit to be closed through the electric lamp or other 65 device placed in the bore 16 of the plug A.

It can be seen that the two sleeves 13 and 17 are electrically connected together by means of the bolts 21 while the central contact 25 is electrically connected by means of 70 the bolt 24 with the contact member 27. And when the cap 35 is placed in position the current will flow through the contact member 27 to one of the contact tongues 36, through one of the wires 38, through the switch 39, back through the other wire 38, through the other contact 36, through the contact member 28, through the bolt 30 to the central contact 31 located in the bore 16 of the lower section 11. 80

From the foregoing description, it can be seen that an exceptionally simple and durable means has been provided for attaching a pendant switch structure through an electric lamp socket in order to facilitate 85 the closing of the circuit through the ordinary electric lamp or other device.

I claim:

A pendant switch structure comprising a 90 body of insulating material having upper and lower sections, and having pockets at the juncture of the upper and lower sections opening through one side of the body, an external contact sleeve carried by the upper section, an internal contact sleeve carried by the lower section, bolts of conducting material extending through said sections and engaging said sleeves to retain the sleeves and sections in place and electrically connect said sleeves, a central contact carried by the upper end of said upper section, a central contact within said lower section, spaced contacts within said pockets adapted to be engaged by cooperating contacts of a circuit completing plug removably engageable with 95 said body, tongues extending from said spaced contacts, means electrically connecting one of said tongues with the central contact of the lower section and anchoring the two contacts to the lower section, and a bolt of conducting material extending through the upper section and holding the upper central contact in place and electrically connecting the same with the tongue of the second spaced contact. 100 105 110

LEONARD G. STURDY.
